N. KASDAN ET AL

COMBINATION VANITY ARTICLE

Filed June 28, 1922

Patented Nov. 11, 1924.

1,515,120

UNITED STATES PATENT OFFICE.

NATHAN KASDAN, OF BRONX, AND DANIEL POLLACK, OF BROOKLYN, NEW YORK.

COMBINATION VANITY ARTICLE.

Application filed June 28, 1922. Serial No. 571,358.

To all whom it may concern:

Be it known that we, NATHAN KASDAN, a citizen of Russia, and a resident of Bronx, in the county of Bronx and State 5 of New York, and DANIEL POLLACK, a citizen of the United States, and a resident of Brooklyn, New York, have invented certain new and useful Improvements in Combination Vanity Articles, of which the following is a specification.

The object of the invention is to provide a combination vanity structure possessing a number of utilities and one which may be conveniently carried and used and furnish 15 all the usual requisites that a lady may require.

The article of our invention is given the general form of a hand mirror comprising a back and a handle, and in carrying out 20 our invention we convert the handle into a receptacle for securely receiving a lipstick and its holder and apply to the front face of said back a mirror, while at the rear face of said back the article is of box- 25 formation and has a hinged lid, said box being adapted to contain a compact and powder puff or the like and the inner face of said lid being preferably equipped with a mirror which may be used when the lid 30 is in open position.

Our invention includes a novel construction of the frame portions of the article from sheet metal, so that the same may be readily produced with the use of dies and 35 excessive weight and expense eliminated.

The handle for the article is hollow, and it may be either rigid with or hinged to the upper or back section of the article, as may be preferred.

40 The invention will be readily understood from the detailed description hereinafter presented, reference being had to the accompanying drawings, in which:

Fig. 1 is a front elevation of a combination vanity article embodying our invention;

Fig. 2 is a rear elevation, with the handle partly broken away, of the same;

Fig. 3 is an edge view of the same;

50 Fig. 4 is a vertical section through the same taken on the dotted line 4-4 of Fig. 1;

Fig. 5 is a front elevation of a modified construction embodying our invention, the 55 modification residing chiefly in hinging the

handle to the upper or back section instead of having the same rigid as in Figs. 1 to 4 inclusive;

Fig. 6 is a central vertical section through the middle portion of the same and is presented to bring out the latch construction by which the handle when unfolded is rigidly held in line with the upper or back section of the article, and

Fig. 7 is an edge view of the article 65 shown in Fig. 5, with the handle illustrated as folded upwardly against the upper section thereof, this construction being desirable when the article is to be carried in a small hand-bag.

In the drawings, referring to Figs. 1, 2, 3 and 4, 10 designates the handle of the article and 11 the main back or body section thereof. The article in general outline is in the conventional shape of a hand 75 mirror, whose back or body portion carries on its obverse face a plate glass mirror 12, and on its reverse face, in accordance with a portion of our invention, a box or container 13 for a powder puff, compact or like 80 equipment, said box preferably being circular in outline and provided with a cover 14 secured thereto by a hinge 15.

The cover 14 is of cap formation, as shown, so as to enlarge the capacity of the 85 box and to receive on its inner flat face a mirror 16 for use when the box 13 is open and its contents are being made use of, said mirror 16 being held in place within the cap or cover 14 by a flat ring 17 tightly 90 engaging the inner surface of the flange of the cap or cover and lapping upon the mirror 16.

The frame construction of the article is 95 important in that thereby we are enabled to produce an attractive article having several utilities at reasonable expense. The general frame comprises three main parts of sheet metal, one part 18 providing the metal portion of the front of the article, another part 19 affording the box 13 and means for securing it in position and the third part 20 constituting the back of the handle 10. The part 18 is shaped in its lower portion to form a hollow shell outlining the vertical front half of the hollow handle 10, and in its upper portion said part 18 is of beveled ring formation, as at 105 21, having a contracted front opening at which the face of the mirror 12 is exposed, 110

said mirror being circular and having a beveled edge matching the inner forwardly converging or beveled surfaces of the ring 21, as shown in Fig. 4. The part 18 constituting the front half of the handle 10 and the ring or frame 21 for the mirror 12 is in one integral piece of sheet metal. The part 19 is shaped to form the circular body of the box 13 and around the same flat base flange 22, along whose peripheral edges, except at the handle 10, the base flange 22 is flanged forwardly and downwardly, as at 23, against the outer surface of the ring 21, whereby to secure the box 13 to the ring 21. Between the base flange 22 and the mirror 12 we interpose a disk 24 of cardboard or the like as a protection for the back of the mirror and to form the bottom of the box 13, said disk 24 being held in position by the flange 22 and the securing flange 23 by means of which the box 13 and flange 22 are connected with the forward portion of the article. The part 20 is shaped to form a hollow shell outlining the vertical back half of the hollow handle 10 and matching the front half of said handle, said halves of the handle meeting and being secured together at their edges to complete the handle. The upper end of the handle 10 is of considerable width and hence has a durable connection with the ring 21, and the back section of the handle is finished off with a straight edge portion 25 which crosses the lower portion of the flange 22 and is soldered or otherwise secured thereto. The parts 18, 19 and 20, each in one integral piece of sheet metal, may thus be readily formed and securely assembled at small expense to produce a convenient and attractive frame for the mirror and other features with which we equip the article.

The outer edge portions of the sides of the box 13 are offset inwardly to form an annular right angle seat 26 to rather tightly receive the edge of the flange or skirt of the cap or cover 14, so that the sides of the box may have smooth uniform surfaces and the cap or cover be capable by reason of a friction fit to remain in closed position when the box 13 is not in use.

The hollow handle 10 is of special importance in that we make provision therein for a sheet metal holder 27 containing a lip-stick 28. The handle 10 at its lower end has a restricted oval opening 29, and in one side of the handle a recess 30 extends upwardly from the opening 29. The holder 27 is of metal and in the form of a split oval tube having therein an auxiliary holder and follower 31 for the lower end of the stick 28.

The follower 31 has a button-head 32 connected therewith by a shank which fits within the recess 30 of the handle and allows the head 32 to lie upon the handle 10 somewhat above the extreme lower end of the

same, said shank also being adapted when the holder 27 is withdrawn from the handle 10, to be slid up along the slot 33 in said holder so as to cause the follower 31 to more or less expose the upper end of the stick 28 above said holder. The holder 27 being in the form of a split tube may be crowded up into the opening 29 and along the inner front and back walls of the handle 10 with a friction fit, so that the holder 70 when not in use will remain in position in the handle and yet may be withdrawn therefrom, with the lip-stick therein, when it is desired to use the same.

The article of our invention thus combines in a small hand-mirror frame, the conveniences of a mirror, a powder puff box and a lip-stick, the whole being compactly and conveniently arranged.

In some instances it may be desirable to hinge the handle of the article so that the handle may be folded up against the mirror for convenience in carrying the article in a small hand-bag, and we illustrate this embodiment of our invention in Figs. 5, 6, and 7, wherein 40 may designate the handle, 41 the ring which holds the mirror 12 and 42 the flange on the base flange 43 of the box 44 which, in this instance, completely encircles the mirror ring 41 and otherwise, as does the base flange 43, corresponds with the construction shown in Figs. 1, 2, 3 and 4. The box 44 except as to the continuity of the flange 42, corresponds with the box 14 of Fig. 4 and thus does not require detailed description. The handle 40 corresponds substantially with the handle 10 of Figs. 1, 2, 3 and 4 except that it is secured to the flange 42 by a spring hinge 45 and is equipped with a small spring latch bolt 46 adapted to interlock with a keeper 47 on the base flange 43 and to be manually released therefrom by means of a slide button-head 48 on said bolt. The spring hinge 45 is adapted to hold the handle 40 folded up against the mirror 12, as indicated in Fig. 7, and when the handle is turned downwardly for use it may be locked in line with the mirror by means of the latch 46 and keeper 47. The handle 40 receives the lip-stick holder 27 the same as does the handle 10, and hence this feature does not require further detailed explanation. The handle 40 is hinged merely for the sake of compactness when it may be desired to carry the article in a small handbag, and the article shown in Figs. 5, 6 and 7 possesses all the conveniences of the article shown in Figs. 1, 2, 3 and 4, but is a little more expensive of manufacture due to the hinging of the handle.

The shank of the slide-head 32 by engaging the lower edge portion of the handle of the article, preferably at the recess 30, serves as a stop to prevent the lip-stick holder from being pushed unduly into the handle.

The metal parts of the article may be nickel-plated or otherwise embellished to render the article attractive and conceal the joints between said parts.

5. What we claim as our invention and desire to secure by Letters-Patent, is:

1. A vanity article in the shape of a hand mirror comprising a handle, a body section equipped with a mirror on its obverse face 10 and a powder puff box on its reverse face having a hinged lid, said handle being secured to said body section and extending from the edge and in the plane thereof, and a toilet-stick holder applied within said 15 handle and removable for use through the end thereof, said handle being hollow and formed with an opening in its lower end closely fitting said holder adjacent to its closed end, leaving the closed end of the 20 holder exposed and said holder normally closing the end of the handle, and said holder being a metal tube adapted to be introduced endwise through said opening and between the front and back inner walls 25 of the handle and containing a follower for the toilet-stick having an operating shank and exposed head therefor, said shank serving as a stop against the lower edge of the handle to arrest undue inward movement 30 of the holder into the handle and said handle being recessed up from the end-opening therein to receive said shank and permit said head to lie at the exterior of the handle in exposed position.
35. 2. A vanity article in the shape of a hand mirror comprising a body section equipped with a mirror on its obverse face and a powder puff box on its reverse face having a cover, a handle hinged to one edge thereof so as to lie in the plane of said section, said handle being adapted to be folded up close 40 against the mirror when the article is not in use, means for locking the handle in its normal operative position for use and a toilet-stick holder applied within said handle and removable for use through the end thereof, said handle being hollow and formed with an opening in its lower end closely fitting said holder adjacent to its 45 closed end, leaving the closed end of the holder exposed and said holder normally closing the end of the handle, and said holder being a metal tube adapted to be introduced endwise through said opening and 50 between the front and back inner walls of the handle and containing a follower for the

toilet-stick having an operating shank and exposed head therefor.

3. A vanity article in the shape of a hand mirror comprising a body section equipped with a mirror on its obverse face and a powder puff box on its reverse face having a cover, a handle hinged to one edge thereof so as to lie in the plane of said section, 60 said handle being adapted to be folded up close to said mirror when the article is not in use, a spring acting to retain said handle in its folded inoperative position, a spring latch for locking the handle in its normal operative position for use and a 65 lip-stick holder applied within said handle and removable for use through the end of the same, said handle being hollow and having an opening in its lower end, and said holder being a metal tube adapted to be 70 introduced endwise through said opening and between the front and back inner walls of the handle.

4. A vanity article in the shape of a hand mirror and of the character described, comprising a handle and a body section having on its obverse face a mirror and on its reverse face a powder puff box having a hinged lid, said body section consisting of a retaining ring engaging the edge of the 80 mirror and said box portion, and said box portion having a base flange at the back of the outer edge portions of said mirror, an edge flange turned over upon and clutching 85 said retaining ring and an outstanding part 90 constituting the body of the box.

5. A vanity article in the shape of a hand mirror and of the character described, comprising a handle and a body section having on its obverse face a mirror and on its reverse face a powder puff box having a hinged lid, said body section consisting of a circular retaining ring extending around 95 the edge of the mirror and said box portion, and said box portion having a circular base flange at the back of the outer edge portions of said mirror, a peripheral flange turned over upon and clutching said retaining ring and a circular part outstanding 100 from the inner edge of said base flange and 105 constituting the body of the box.

Signed at New York city, in the county of New York and State of New York, this 26th day of May, 1922.

NATHAN KASDAN.
DANIEL POLLACK.
